US00D721811S

(12) **United States Design Patent**
Zakhem et al.(10) **Patent No.:** **US D721,811 S**
(45) **Date of Patent:** **** Jan. 27, 2015**(54) **ORTHODONTIC BRACKET**(71) Applicant: **RMO, Inc.**, Denver, CO (US)(72) Inventors: **Antoun Halim Zakhem**, Highlands Ranch, CO (US); **Leon W. Laub**, Fort Collins, CO (US); **Martin Randolph**, Littleton, CO (US); **Jeffrey Allen Smith**, Denver, CO (US); **Nam Trinh**, Highland Ranch, CO (US)(73) Assignee: **RMO, Inc.**, Denver, CO (US)(**) Term: **14 Years**(21) Appl. No.: **29/471,219**(22) Filed: **Oct. 29, 2013**(51) LOC (10) Cl. **24-99**(52) U.S. Cl. **USPC D24/180**(58) **Field of Classification Search**USPC **D24/176-182; 433/8-18**
See application file for complete search history.(56) **References Cited**

(74) Attorney, Agent, or Firm — Sheridan Ross P.C.

(57) **CLAIM**

The ornamental design for an orthodontic bracket, as shown and described.

DESCRIPTION

FIG. 1 is a front perspective view of the orthodontic bracket showing the new design;

FIG. 2 is a rear perspective view thereof;

FIG. 3 is a right elevation view thereof;

FIG. 4 is a left elevation view thereof;

FIG. 5 is a rear elevation view thereof;

FIG. 6 is a front elevation view thereof;

FIG. 7 is a top plan view thereof; and,

FIG. 8 is a bottom plan view thereof.
